UNITED STATES PATENT OFFICE.

HERBERT E. TOWNSEND, OF EAST PROVIDENCE, RHODE ISLAND, ASSIGNEE TO BROWN
AND SHARPE MANUFACTURING COMPANY, OF PROVIDENCE, RHODE ISLAND, A
CORPORATION OF RHODE ISLAND.

CUSHIONING DEVICE FOR REVERSING MECHANISM.

Application filed June 17, 1922. Serial No. 569,135.

To all whom it may concern:

Be it known that I, HERBERT E. TOWNSEND, a citizen of the United States, residing at East Providence, in the county of Providence and State of Rhode Island, have invented certain new and useful Improvements in Cushioning Devices for Reversing Mechanism, of which the following is a specification.

10 My invention relates to improvements in cushioning devices for reversing and driving mechanisms for reciprocating loads.

Certain machines, such as for example, grinding machines, planers, etc., are provided with reciprocating tables which carry the work or the tool. In order to periodically reverse the direction of travel of the table it is usual to provide a reversible clutch which may be automatically actuated 20 to reverse the direction of rotation of the driving member and hence the direction of travel of the table. Whenever the clutch is actuated to reverse the direction of table travel it is apparent that a shock in the driving mechanism occurs. It is the prevention of this shock and corresponding strain on the gears and driving members at which my invention aims.

It is thus one object of my invention to 30 provide a means by which the driven member is gradually retarded and accelerated, so that with the assistance of springs the shocks incidental to reversing are yieldingly cushioned. By the use of my spring actuated and screw controlled cushioning device, it is possible to greatly increase the speed at which the table may be driven, and hence the cutting rate and efficiency of the whole machine.

40 A further object of my invention is to produce a smoother surface on the ground article. One reason for this result is that the usual shock and vibration is greatly lessened thereby securing a uniformity in grinding even when grinding at a greater speed.

Another object of my invention is to eliminate any necessity for providing for lost motion during the reversing period. This 50 is automatically taken care of by my yielding cushion.

These and such other features of my invention as may hereinafter appear will be best understood from a description of one

embodiment thereof, such as for instance is 55 shown in the accompanying drawings which illustrate an adaptation of my invention to the reversing mechanism of a grinding machine.

In the drawings, Figure 1 is a front skeleton view of a grinding machine, showing the table, the clutch, the cushioning device, and the train of gearing leading to the table.

Figure 2 is a detailed section of the cushioning device and its adjacent parts.

Figure 3 is a cross section of the cushioning device along the lines 3—3 of Figure 2.

Figure 4 is a detailed sectional view of the traversing nut used in the cushioning device.

Figure 5 is a perspective view of one of a 70 set of washers used in the cushioning device.

In the drawings, wherein like reference characters indicate like parts throughout, 1 is the body of the grinding machine on which is mounted the reciprocating table 2. 75 The dogs 3 are adjustable longitudinally in a runway 4 on the front edge of the table 2, and are adapted to trip at the desired intervals the long arm 5^a of the reversing lever 5. The reversing lever 5 is suitably mounted on the body 1, and its short arm 5^b is bifurcated and has mounted at each end of the bifurcations 5^c the inwardly projecting extensions 5^d which register in grooves 8^a of the sliding clutch member 8. This clutch 85 member 8 is constructed to slide longitudinally on the shaft 9 and is usually splined thereto (Fig. 2). It has on opposite ends the clutch faces 8^b and 8^c. Loosely mounted on the shaft 9, and spaced sufficiently apart 90 for adequate movement of the short arm 5^b of the reversing lever 5 are the clutch members 10 and 11. The clutch members 10 and 11 have on their opposed faces the clutch faces 10^b and 11^b 100 for engagement with the clutch faces 8^b and 8^c of the clutch member 8. These clutch faces preferably comprise positively engaging teeth. It is thus seen that when the clutch face 8^b is in engagement with the face 10^b the shaft 9 is driven in one direction, but when the clutch member 8 is thrown over by the reversing lever 5 so that the opposite

105

clutch face 8^c is in engagement with the face 11^b of the clutch member 11 the shaft 9 is driven in the opposite direction. The driving shaft 9 rests on the bushings 13 and 13' 5 which may be conveniently mounted on the body 1 of the grinding machine. Up to this point I have described a form of reversing clutch commonly used in grinding machines. By a suitable train of gearing power has 10 been transmitted directly to the table 2 from the driving shaft 9. However I have interrupted this direct drive and now transmit motion from shaft 9 to the table 2 through my interposed cushioning device, 15 which forms a connecting unit of the drive and which I will now describe in more detail.

On the opposite side of the bushing 13 from the clutch member 11 I have keyed to 20 the shaft 9 a small pinion gear 14. Meshing with this small pinion 14 is the gear 15 which is suitably mounted on the split casting 26, which forms the housing of my device and which I will explain later. The 25 gear 15 has projecting longitudinally from one side thereof the large cylindrical sleeve 15^a (Fig. 2) which encircles for the desired distance the shaft 16, which is journaled in extensions from the bracket 24, as explained 30 later. As this longitudinally projecting sleeve 15^a is formed integral with the gear 15 it is rotated therewith. This longitudinally projecting sleeve has cut on its inner periphery the longitudinal grooves 15^b and 35 15^{b'}, in the construction as shown in Figure 3 six in number. Adapted to slide longitudinally between the shaft 16 and the longitudinally projecting sleeve 15^a is the traversing nut 17. This is cylindrical in shape and has 40 on its outer periphery the central annular shoulder 17^a, which has projecting radially therefrom the splines 17^b as shown in Fig. 3, three in number, adapted to register with and slide longitudinally in the alternate 45 grooves 15^b. The shoulder 17^a has end faces 17^c. The traversing nut 17 is hollow and has cut on its inner periphery the helical threads 17^d. Mounted on the bushings 16^a which encircle the shaft 16 is the gear 18 50 which has formed integral therewith and projecting longitudinally therefrom in the same direction as the cylindrical sleeve 15^a projects from the gear 15, the sleeve 18^a. This longitudinally projecting sleeve 18^a 55 has cut on its outer periphery the helical threads 18^d, adapted to engage the helical threads 17^d on the inner periphery of the traversing nut 17. As seen in Fig. 2, the longitudinally projecting sleeve 15^a approximately encloses the longitudinally projecting sleeve 18^a. The traversing nut 17 is shorter than the longitudinal distance allotted to it between the sleeves 15^a and 18^a, and is free to move lengthwise thereof, its 60 longitudinal splines 17^b being in engagement

with the alternate longitudinal grooves 15^b, and its helical threads 17^d being in engagement with the helical threads 18^d. When the sleeve 15^a is revolved, as the splines 17^b are in engagement with the grooves 15^b, driving 70 force is exerted on the traversing nut 17. This force is resolved into two moments by the helical threads 17^d, one moment of which tends to force the traversing nut 17 longitudinally of the sleeves 15^a and 18^a, while the other tends to rotate the longitudinal sleeve 18^a. This rotary moment is taken up 75 by the helical threads 18^d thus rotating the longitudinally projecting sleeve 18^a and its integral gear 18. To yieldingly cushion the longitudinal movement of the traversing nut 17, and to take up the shocks of reversal. 80 I provide the springs 19 and 19', shown extended and compressed respectively in Figure 2. These springs 19 and 19' are coiled around the longitudinally projecting sleeve 18^a and are enclosed by the longitudinally projecting sleeve 15^a. One end of the spring 19 (Fig. 2) rests against a washer 19^a which bears against one face 18^c of the gear 18. 85 One end of the spring 19' (Fig. 2) rests against a washer 19'^a which bears against the thrust collar 20. The other ends of the springs 19 and 19' press against the washers 21, the opposite sides of which contact the faces 17^c of the traversing nut 17. These washers 21 have projecting from their outer periphery the splines 21^a, as shown in Figure 5, three in number, adapted to slide longitudinally in the alternate grooves 15^{b'} of 90 the longitudinally projecting sleeve 15^a (Fig. 3). Centrally of the alternate grooves 15^{b'}, and suitably secured therein by the rivets 22 are the keys 23 which extend longitudinally a short distance each side of the 95 rivets 22 (Fig. 2), and limit the longitudinal movement of the washers 21. This prevents the springs 19 and 19' from becoming unduly extended and determines the point 100 of reversal more accurately. It is apparent from the above that the springs 19 and 19' yieldingly limit the longitudinal movement of the traversing nut 17, and are uniformly controlled in their action by the helical threads 17^d and 18^d. Though I have shown 105 a method of controlling the action of the elastic members 19 and 19' by the helically threaded screws 17^d and 18^d, it is obvious 110 that any other suitable method may be employed. 115

As the cushioning effect of the springs 19 and 19' is increased as they are compressed, and thus the longitudinal movement of the traversing nut 17 correspondingly decreased the rotary driving force of the helical threads 17^d against the helical threads 18^d of the longitudinally projecting sleeve 18^a is correspondingly increased. When the spring 19' is sufficiently compressed, the longitudinal movement of the traverse nut is 120 125

stopped, and the rotary force, transmitted from the longitudinally projecting sleeve 15^a to the nut 17 by the walls of the grooves 15^b in the sleeve 15^a coming into engagement 5 with the splines 17^b of the traversing nut 17, is brought to bear against the sleeve 18^a by the interlocking of the helical threads 17^a and 18^a, and the gear 18, is rotated at a constant rate. The yielding cushion 10 19' continues to take up the longitudinal moment of the nut 17 while its entire rotary moment is transmitted as explained to drive the gear 18. When the shaft 9 is taken out of driving engagement, the momentum of 15 the table 2 causes the normally driven gear 18 to act for a short interval of time as a driving gear. This temporary driving motion is transmitted through the helical threads 18^a and 17^a to the traversing nut 17 20 and tends to drive it back along the sleeve 18^a. As the traversing nut 17 is thus driven against the now extended spring 19 and this is partially compressed, it is apparent that the forward movement of the table and its 25 connecting members will be gradually and without shock retarded from the driving rate to temporary rest.

Though I have shown an intermediate member or traversing nut 17, it is clear that 30 this element may be omitted without departing from the spirit of my invention, for the driven member or sleeve 15^a might while being rotated be moved longitudinally of the driving member against a yielding cushion 35 and power transmitted in that fashion.

My cushioning device may be supported and enclosed conveniently as follows: Mounted on the body 1 of the grinding machine is the bracket 24, which supports the 40 bearings 24^a in which is journaled the shaft 16. As stated the longitudinally projecting sleeve 18^a rotates on bushings 16^a supported by the shaft 16. Enclosing the end of the sleeve 18^a is the thrust collar 20 which is 45 held in position by the locknut 25. My cushioning device is enclosed and supported by the housing 26, cast with a base 26^a adapted to rest on the supporting bracket 24. The housing 26 supports the bushing 50 27 which surrounds the sleeve 15^a and may be split as at 26^b for convenient removal. The upper portion of the split housing 26 usually has cast thereon an extension 26^c adapted to receive the reduced portion 13^a 55 of the bushing 13. Meshing with the gear 18 (Fig. 1) is the pinion 30^a formed at one end of the sleeve 30 which is rotatively mounted on a reduced extension 9^a of the driving shaft 9 and secured thereto by a 60 locknut, as shown. On the opposite end of this sleeve 30 is a bevel gear 30^b which meshes with a bevel gear 31^a keyed to one end of the shaft 31. The shaft 31 has keyed at its opposite end, disposed in front of 65 the cushioning device and shaft 9, the pin-

ion 31^b. The pinion 31^b meshes with the gear 32^a (shown in Fig. 1 partially broken away) keyed to the shaft 32 which has keyed at its rear end the small pinion 32^b. This pinion 32^b meshes with a gear 33 supported in a bracket 34 which extends from the body 1 of the grinding machine. The gear 33 in turn meshes with the rack 35 of the table 2.

Figure 1 illustrates the clutch member 8 in neutral position. Figure 2 illustrates the clutch member 8 in driving engagement with the co-operating clutch member 10, with the table 2 being driven at the desired uniform rate as the spring 19' is shown compressed.

In operation, the clutch member 8 is moved by the short arm 5^b of the reversing lever 5 from driving engagement with the clutch member 11 to driving engagement 85 with the clutch member 10. The direction of rotation of the shaft 9 is immediately reversed and this reversal of motion is immediately transmitted by means of the pinion 14 and gear 15 to the longitudinally projecting cylindrical sleeve 15^a. The sleeve 15^a is now rotating in the opposite direction from what it was a moment before. This causes the walls of the grooves 15^b on the inner periphery of the sleeve 15^a to immediately bear against the opposite sides of the splines 17^b of the traversing nut 17. As the helical threads 17^a and 18^a are of relatively low pitch the force of the then compressed spring 19 is not sufficient to 90 throw the traversing nut back along the sleeve 18^a. As stated, rotative force is brought to bear on the traversing nut 17. As the helical threads 17^a are inclined this pressure tends both to move the nut 17 95 longitudinally of the sleeve 18^a, and to exert a straight rotary driving pressure on the sleeve 18^a through the medium of the threads 18^a. The longitudinal movement tends to drive the traversing nut 17 longitudinally of the sleeve 18^a. There is however a small amount of rotary driving force 100 always exerted against the sleeve 18^a. The face 17^c of the traversing nut 17 now strikes against the washer 21, and the spring 19' bearing against the washer 21 presents a yielding cushioning resistance to the further longitudinal movement of the traversing nut 17. As the spring 19' is further compressed, the resistance to the longitudinal 105 movement of the traversing nut 17 is further increased, and the driving action of the nut 17 against the sleeve 18^a correspondingly increased. As stated the helical threads 17^a and 18^a both assist in offering 110 resistance to the longitudinal movement of the nut 17 and render uniform the resistance of the elastic member 19'. It is obvious that the spring 19' provides in addition a means whereby the initial starting shock 115 120 125 130

of the reversing mechanism is yieldingly cushioned and absorbed. When the spring 19' is sufficiently compressed, as further longitudinal movement of the traversing 5 nut is no longer possible, the force exerted on the traversing nut 17 bears against the threads 18^a and is thus transmitted thereby to the gear 18. This rotary movement is transmitted at a uniform rate by means of 10 the gearing described above to the table 2. When the clutch mechanism is reversed, the table continues to travel of its own momentum in the same direction. This forward movement is transmitted back through 15 the train of gearing to the gear 18. This normally driven member thus acts for a short interval of time as a driving member, and the threads 18^a bearing against the threads 17^a of the traversing nut 17 tend 20 to drive it back along the sleeve 18^a. As this is driven against the now extended spring 19 and the spring 19 partially compressed, it is apparent that the forward movement of the table and its connecting 25 members, will be gradually and without shock retarded from the driving rate to temporary rest. Then the driving action of the sleeve 15^a brings itself to bear against the traversing nut 17, and the driving 30 motion is yieldingly accelerated as explained. It is seen that as the rotation of the shaft 9 is reversed, this reversing motion and shock will be repeatedly cushioned and the rotary motion imparted from said shaft 35 will be at first acceleratingly, then uniformly for the desired period of the table travel and finally retardingly transmitted to the table 2, the springs 19 and 19' being alternately compressed at each reversal of the 40 table. This operation is repeated in running the machine.

What I claim as new and desire to secure as Letters Patent, is—

1. A cushioned reversing and driving 45 mechanism for reciprocating loads, having in combination, a clutch mechanism for rotating a shaft alternately in opposite directions, a longitudinally extending cushion-enclosing sleeve, means for engaging this 50 sleeve with the driving shaft to impart rotary motion thereto, grooves formed on the inner periphery of said sleeve, a hollow cylindrical traversing nut containing on its outer periphery splines to engage the grooves 55 in said sleeve, and threads on its inner periphery, a threaded sleeve adapted to engage the threads on the inner periphery of said traversing nut, a set of springs coiled around the threaded sleeve and enclosed by the 60 grooved sleeve, washers intermediate said 65 springs and traversing nut, and means extending from the threaded sleeve to drive the reciprocating load.

2. A cushioned reversing and driving mechanism for reciprocating loads, having 70 in combination a clutch mechanism for rotating a shaft alternately in opposite directions, a longitudinally extending cushion-enclosing sleeve, means for engaging this sleeve with the driving shaft to impart rotary motion to said sleeve, grooves formed on the inner periphery of said sleeve, a hollow cylindrical traversing nut containing on its outer periphery splines to engage the grooves in 75 said sleeve and helical threads on its inner periphery, a threaded sleeve adapted to engage the helical threads on the inner periphery of said traversing nut, a set of springs coiled around the threaded sleeve and enclosed by the grooved sleeve, washers intermediate 80 said springs and traversing nut, keys secured medially the alternate grooves of the grooved sleeve, and means extending from the threaded sleeve to drive the reciprocating load.

3. A cushioned reversing and driving mechanism for reciprocating loads, having in combination, a clutch mechanism for rotating a shaft alternately in opposite directions, a longitudinally extending cushion-enclosing sleeve, means for engaging this sleeve with the driving shaft to impart rotary motion to said sleeve, grooves formed on the inner periphery of said sleeve, a hollow cylindrical traversing nut containing on its outer periphery splines to engage the grooves in 90 said sleeve and threads on its inner periphery, a threaded sleeve adapted to engage the threads on the inner periphery of said traversing nut, a set of springs coiled around the threaded sleeve and enclosed by the grooved sleeve, and means extending from the threaded sleeve to drive the reciprocating load.

4. A cushioned reversing and driving mechanism for reciprocating loads, having 100 in combination, a clutch mechanism for rotating a shaft alternately in opposite directions, a rotary cover, means for engaging this cover with the driving shaft to impart 110 rotary motion thereto, grooves formed on the inner periphery of said cover, a longitudinally movable connecting member containing on its outer periphery splines to engage the grooves in said cover and helical threads on its inner periphery, a rotary internal member helically threaded to engage the helical threads on the inner periphery of said connecting member, spring means 115 adapted to longitudinally encircle the internal member and be enclosed by the cover, and means to transmit the power from the internal member to the reciprocating load.

In testimony whereof I affix my signature.

HERBERT E. TOWNSEND.
